CAN OPENER

Harry L. Dazey, St. Louis, Mo., assignor to Dazey
Churn & Manufacturing Co., St. Louis, Mo., a
corporation of Missouri

Application March 15, 1935, Serial No. 11,215

6 Claims. (Cl. 30—3)

This invention relates to can openers and more particularly to can openers of the type embodying a cutting element and a rotating feeding device which operates to move the can to cause a wall thereof to be severed by the cutting element. The can opener herein described and claimed provides certain improvements in the device which is set forth in my copending application filed 5 August 16, 1934, Serial No. 740,098.

10 An object of this invention resides in the provision of a can opener having improved operating characteristics, such improvements being especially directed to ease and facility of manipulation and to the elimination or substantial reduction of metal particles or shearings heretofore unavoidably produced by the cutting element. Obviously, the production of such shearings is highly undesirable particularly in connection with the opening of cans containing foodstuff.

20 The foregoing object is attained in the present device by the provision of a cutting element or blade which, normally held in a predetermined cutting position, is adapted to turn or rock when it encounters a can portion that presents an obstacle in the blade path, and adjusts itself to a position whereby it may readily pass around the obstacle instead of shearing or cutting through the same. In cans of conventional construction the longitudinal seam provides an obstruction to the 25 blade, and when the blade of an ordinary can opener encounters this seam, the device becomes stalled, whereupon an increased manipulative effort is required to continue the can opening operation. If there is sufficient traction between 30 the feed wheel and can so that no slipping takes place, the obstructing portion of the seam becomes sheared or shaved, the shavings dropping into the contents of the can. This condition is avoided in the device of the present invention by 35 the provision of a blade which is arranged to pivot or turn about an axis longitudinal of the blade. The blade, after encountering the obstruction, is cammed or canted thereby from its normal 40 position to an angular position in which the blade is readily adapted to pass around the obstruction. The advantages of the presently described self-adjusting blade are also evidenced when the device is used to open a square-shaped can, the corner portions of which are especially 45 difficult to cut by prevailing types of can openers.

50 Another object of this invention resides in the provision of an improved self-adjusting blade in combination with means for moving a can relative to the blade and means for holding the can 55

in position for proper operation thereon by the blade.

These and other objects and advantages are attained by the construction shown in the accompanying drawing, wherein, for purposes of 5 illustration, is shown a preferred embodiment of my invention and wherein:

Fig. 1 is a side elevational view of the device of my invention; Fig. 2 is a sectional view taken at line 2—2 of Fig. 1; Fig. 3 is a sectional view 10 similar to the showing of Fig. 2, illustrating parts of the device as disposed for operation on a can, a fragment of which is shown; Fig. 4 is a top plan view of the blade housing; and Figs. 5 and 6 are sections taken at line 5—5 of Fig. 3 illustrating 15 the manner in which the blade moves to allow it to pass a seam or other internal projection of the can without cutting through the same.

Referring now by characters of reference to 20 the drawing, in Fig. 1 the operating parts of the can opener are shown mounted on a support in the form of an elongated sheet metal arm 10 which is adapted to be secured by suitable means indicated generally at 11 to a wall or other supporting structure. The means by which member 10 is fastened to the supporting structure forms 25 no part of the present invention and accordingly will not be described in detail.

The member 10 is provided at its lower outer 30 margin with a downwardly projecting portion which is bent outwardly to form a horizontal flange 12 which is adapted to contact the side of the can as shown in Fig. 3. The flange 12 serves to stabilize, or prevent undue vibration 35 of the can during the operation of the device.

Describing now the means for supporting and moving the can relative to the cutting element, the supporting arm 10 is provided with a circular opening located above the flange 12, in which opening is journaled the forward end of a cylindrical bushing or hub 13, the forward end surface of said hub lying flush with the so-called front side of the member 10. The hub 13 is 40 formed with an annular flange 14 which is confined between member 10 and the outwardly dished portion 15 of a plate 16 secured at the back side of member 10, the hub 13 projecting 45 through an opening in the said dished portion of plate 16 and carrying a manipulating handle 17 for rotating the hub 13. A toothed disc or feed wheel 18 is secured to one end of a shaft 19, journaled in and extending through the hub 13 in 50 off-center relation thereto, a crank 20 for actu- 55

ating the shaft 19 being secured in a suitable manner to the said shaft.

It will now appear that movement of the handle 17 through an arc of 180 degrees causes the feed wheel 18 to be shifted toward or from the pointed end of a cutting element 21 mounted above the feed wheel. In Fig. 2 the feed wheel is shown disposed in its lowermost position whereby its upper surface is spaced downwardly from the pointed end of the element 21. When so disposed the feed wheel is adapted to have the external bead of a can seated thereon. By turning the handle 17 through one-half revolution the feed wheel is shifted, displacing the can upwardly and causing its top wall to be punctured by the cutting element, as appears in Fig. 3. Lugs, not shown, projecting laterally from plate 16 form abutments for handle 17 and limit its range of turning movement to substantially 180 degrees. One of such lugs is arranged to be engaged by the handle 17 when disposed in the position shown in Fig. 2, and another of such lugs determines the uppermost position of the feed wheel by reason of the engagement of said lug with handle 17 when the latter is disposed as shown in Fig. 3.

In accordance with this invention, means are provided for holding the can bead in pressure engagement with the feed wheel when that element is raised to its operating position (Fig. 3). In the present example such means include an elongated sheet metal arm 22 disposed horizontally and flatwise upon member 10 above the feed wheel. The arm 22 is pivotally connected at one of its ends to member 10 by a pivot pin 23, the opposite end of arm 22 being bent to overlap a recessed edge at the outer end of member 10 as indicated at 24. A horizontal, outwardly projecting flange 25, formed on arm 22, is adapted to engage and bear upon the upper edge of the can bead. Upward pivotal movement of arm 22 is opposed by the action of spring 26, compressed between an ear 27 struck from member 10, and the flange 25. This spring is held in place by means of studs carried by the ear 27 and flange 25, which studs project into the ends of the spring.

Describing now the cutting element and improved mounting arrangement thereof, the cutting element is supported within an elongated housing formed of sheet metal and comprising a back wall 28, spaced side walls 29, top wall 30, and front wall 31. The back wall 28 of the housing lies flatly against the base plate 10 and is secured thereto, in the present example, by a rivet 32 and a flat-headed screw 33, the head portion 34 of the said screw providing an abutment for the cutting element or blade 21, as shown in Fig. 2. The front wall 31 has lugs 35, (Fig. 1), projecting from opposite side edges thereof, which lugs are seated upon forwardly projecting ears 36 at the lower forward edges of side walls 29. A pin 37 carried by and extending between ears 36 serves to fasten the front wall 31 to the side walls of the housing.

The blade 21 is disposed vertically in the housing and projects downwardly through the open lower end thereof. The blade is provided at its upper end with a longitudinally projecting finger 38 which fits loosely in a suitable opening formed in the upper wall 30 of the housing. By reason of the loose connection between upper wall 30 and finger 38, the blade is adapted for swivelling movement, which term is intended to cover a turning movement of the blade about its longitudinal or vertical axis, as will be understood by

comparing the blade positions of Figs. 5 and 6, and also an outward swinging movement of its lower or cutting end, as shown by the relative blade positions of Figs. 2 and 3. A coil spring 39 provides a yieldable, resilient support for blade 21, the said spring being disposed on coaxial studs 40 on the blade 21 and front wall 31. The spring 39 normally forces the blade against the abutment 34 as shown in Fig. 2, yet permits the blade to yield, or otherwise adjust itself when it encounters an internal obstruction or irregularity such as the longitudinal internal seam of the can, so as to ride or pass around rather than cut through the said obstruction.

The operation of my improved can opener is believed to be obvious from the foregoing description, but for purposes of completeness may be described as follows: The handle 17 is initially swung to the position shown in Fig. 2 which causes the feed wheel, by reason of its eccentric mounting on hub 13, to be disposed with its upper periphery spaced below the pointed end of the blade 21. The can is then applied to the opener with its vertical side wall contacting the outer face of the feed wheel and lug 12, and its upper marginal seam or bead resting upon the upper surface of the feed wheel. The handle 17 is next swung to the position shown in Fig. 3 to elevate the can and cause its upper horizontal wall to be punctured by the blade 21, the marginal bead engaging the yieldable abutment 25 and being pressed thereby against the toothed surface of the feed wheel. Now by turning crank 20 the can rotates bodily and the top thereof is sheared as it makes a complete revolution. From Figs. 5 and 6 it will appear that when the leading edge of the blade encounters an obstruction, such as an internally projecting seam portion, it will be cammed outwardly, the blade assuming an angular position, whereby it is readily adapted to ride over the said obstruction with little or no increased resistance to the operating force applied to handle 20.

The device of the present invention operates in an improved manner on cans having substantially square or slightly rounded corners, this by reason of the fact that the blade, when encountering the corner portion of a square can, adjusts itself angularly to a position in which it can most readily pass the said corner portion.

The invention has been described with reference to a single, presently preferred embodiment thereof. It should be understood however that the invention is not limited to any one particular embodiment except as the same is fairly defined by the appended claims.

I claim:

1. In a can opener including a base plate and a feed wheel for moving a can relative to the base plate, an arm projecting from the base plate above said feed wheel, a cutting element projecting downwardly from said arm, means forming a swivel connection between the cutting element and said arm, and a spring urging said blade inwardly toward the feed wheel, adapted yieldingly to resist swivelling movement of the blade.

2. In a can opener including a base member and a feed wheel for moving a can relative to the base member, an arm projecting from the base member above the feed wheel, a substantially flat, elongated blade element having its longitudinal axis projecting downwardly from said arm toward the feed wheel, means forming a swivel connection between said blade element and arm whereby the lower cutting end of the blade is permitted to swing outwardly away from the feed wheel and

the blade is also permitted to turn about its longitudinal axis, and a spring disposed yieldingly to resist movement of the blade element.

3. A can opener comprising a base plate, a feed wheel mounted on one side of the base plate, a blade housing projecting laterally from the base plate above the feed wheel, a blade having a vertical axis disposed in said housing and projecting through the lower end thereof toward the axis of said feed wheel, and a spring in said housing which provides a flexible mounting for the blade and normally maintains the same parallel to the feed wheel, said blade being adapted to rock angularly about its vertical axis against pressure from said spring.

4. A can opener comprising a base plate, a feed wheel mounted on one side of the base plate, a blade housing projecting laterally from the base plate above the feed wheel, a vertical blade in the housing projecting through the lower end thereof toward the axis of said feed wheel, means pivotally connecting the upper end of said blade to the upper wall of said housing whereby the blade is adapted to turn about a vertical axis therethrough, and a spring connected between said blade and a wall of said housing adapted yieldingly to oppose turning movement of the blade as aforesaid.

5. In a can opener including a base plate, a feed wheel mounted for rotary and shifting movement on the base plate, a yieldable pressure member disposed to bear upon the upper end of a can and force the same into operative engagement with the feed wheel, a blade housing secured to the base plate in overlying relation to the feed wheel, a blade projecting through the bottom of said housing, adapted to overlap the outer end face of the feed wheel, and a spring in said housing providing a flexible carrier for said blade.

6. In a can opener including a base plate, a feed wheel mounted for rotary and shifting movement on the base plate, a yieldable pressure member disposed to bear upon the upper end of a can and force the same into operative engagement with the feed wheel, a blade housing projecting from the base plate above the feed wheel, a blade element projecting downwardly through the bottom of said housing, terminating in a can-piercing and cutting portion which overlaps the outer end face of the feed wheel when the latter is shifted to operating position, means forming a swivel connection between the upper end of the blade element and the top wall of the housing, and spring means in said housing adapted yieldingly to maintain the blade in a predetermined cutting position.

HARRY L. DAZEY.
